UNITED STATES PATENT OFFICE.

JOHN B. GRIFFIN, OF NEW BRITAIN, CONNECTICUT, ASSIGNOR TO LANDERS, FRARY & CLARK, OF NEW BRITAIN, CONNECTICUT, A CORPORATION OF CONNECTICUT.

PERCOLATOR-PUMP.

1,251,509.

Specification of Letters Patent.

Patented Jan. 1, 1918.

Application filed June 8, 1916. Serial No. 102,488.

To all whom it may concern:

Be it known that I, JOHN B. GRIFFIN, a citizen of the United States, and a resident of New Britain, in the county of Hartford, 5 State of Connecticut, have invented certain new and useful Improvements in Percolator-Pumps, of which the following is a specification.

My invention relates to percolator pumps 10 of the general type shown in my Patent No. 1,142,322. The object of the present invention is to provide a new and useful method of constructing and supporting the valve of a percolator pump.

15 In the drawings—

Figure 1 is a side view, partly in section, of a percolator pump embodying my invention, a portion of the percolator bowl being shown in dotted lines.

20 Fig. 2 is a detail perspective view of the sleeve.

Referring to the drawings, *a* is the well or heating chamber for the water, on the upper end of which there is properly mounted 25 a tube *b* extending upward to a point above the container *c*. The tube *b* has an orifice in its side as indicated at 2, through which the water from the bowl may enter into the well *a* to be there heated and expanded so that it would be expelled upwardly through the tube *b*. Fitted into the lower end of the tube *b* is a sleeve 3. As illustrated, this sleeve is cut away adjacent the orifice 2, as indicated at 4. It is immaterial whether a section of the sleeve is entirely cut away or a portion left at the lower part as here illustrated. The vertical edges 5 of this cut-away portion are notched as at 6, leaving overhanging tips, 7. The lower 0 edges of the notches preferably join the vertical edges 5 by rounded corners 8, providing an easy rocking bearing for the valve.

10 is the valve shaped to fit closely against the inner wall of the tube *b* and cover the 5 orifice 2. At either side it has wings 11 with projections 12 which are preferably rounding and fit loosely in the notches 6, having curved parts resting on the rounded corners 8. The projections 12 extend under the tips 0 7 and the valve is thus held against accidental displacement relative to the sleeve. The wings 11 are notched as at 13, so that the valve may swing inwardly toward the center of the tube to permit a full opening 5 of the orifice 2.

It will be seen from this construction that the sleeve 3, which is preferably of a single piece of metal, provides at opposite points in the tube bearings upon which the valve rocks without having any part extending 60 across the tube to obstruct the passage of the water, or to give opportunity for the lodgement of sediment. At the same time it provides an efficient rocking support for the valve, preventing the displacement of the 65 valve transversely of the tube and longitudinally of the sleeve, and in fact provides an extremely simple and efficient construction. The sleeve 3 may be secured in position in the tube in any desired manner. 70

While in the drawings there is shown but a single orifice and a single valve, and but one side of the sleeve is cut away, still it is obvious that it could be cut away at the opposite side, and another orifice and another valve utilized.

This invention involves the mode of operation of the structure described in my patent above mentioned, in that the valve is an upstanding valve so that the tendency 80 of the passage of the water and steam upward in the tube is to close the valve.

In accordance with the provisions of the patent statutes, I have described the principle of operation of my invention, together 85 with the apparatus which I now consider to represent the best embodiment thereof; but I desire to have it understood that the apparatus shown is only illustrative, and that the invention can be carried out by other 90 means.

I claim as my invention:—

1. In a percolator pump, a tube having an orifice in its wall, a sleeve fitted within said tube and cut away at opposite points to 95 form bearing surfaces, a valve fitting the contour of said tube to close the orifice, oppositely extended circumferential projections at the lower edge of said valve fitted to and adapted to rock upon the bearing surfaces of said sleeve.

2. In a percolator pump, a tube having an orifice in its wall, a sleeve fitted within said tube and cut away at opposite points to 105 form bearing surfaces, a valve fitting the contour of said tube to close the orifice, oppositely extended circumferential projections at the lower edge of said valve fitted to and adapted to rock upon the bearing surfaces of said sleeve, and means on said 110

sleeve to prevent accidental displacement of said valves.

3. In a percolator pump, a tube having an orifice in its side, a valve for the orifice located inside of said tube and provided with wings extending from opposite sides and lying against the wall of the tube, a support arranged circumferentially within said tube and provided with opposite rounded bearing surfaces upon which said wings rest, and tips on said support overlying a portion of said wings.

4. In a percolator pump, a tube having an orifice in its side, a valve for the orifice located inside of said tube and provided at opposite sides with wings which lie against the wall of said tube, projections

from the lower part of said wings, and a support positioned in the lower end of said tube provided with opposite rounded surfaces upon which said projections rest.

5. In a percolator pump, a tube having an orifice in its side, a sleeve fitted in the lower end of said tube cut away in its upper part for a distance slightly less than half its circumference, notches in the vertical edge of said cut-away portion, and a valve located within said tube and operatively positioned with respect to the orifice and provided with side projections entering said notches.

JOHN B. GRIFFIN.
